(57) **CLAIM**

The ornamental design for a cycle, as shown and described.

DESCRIPTION

FIG. 1 is a front perspective view of my new design showing a cycle;

FIG. 2 is rear perspective view of the cycle of FIG. 1;

FIG. 3 is a side elevational view of the cycle of FIG. 1;

FIG. 4 is another side elevational view of the cycle of FIG. 1, which is the opposite side of that shown in FIG. 3;

FIG. 5 is a front view of the cycle of FIG. 1;

FIG. 6 is a rear view of the cycle of FIG. 1;

FIG. 7 is a top plan view of the cycle of FIG. 1;

FIG. 8 is a bottom plan view of the cycle of FIG. 1;

FIG. 9 is an exploded view of a top perspective view of the cycle of FIG. 1;

FIG. 10 is a detail view of the frame of the cycle of FIG. 1;

FIG. 11 is a detail view of the frame of the cycle of FIG. 2;

FIG. 12 is a detail view of the frame of the cycle of FIG. 4; and,

FIG. 13 is a detail view of the frame of the cycle of FIG. 7.
